UNITED STATES PATENT OFFICE

HARRY BARKBY, OF NEW CASTLE, PENNSYLVANIA, ASSIGNOR TO STEARNES COMPANY, OF CHICAGO, ILLINOIS, A CORPORATION OF ILLINOIS

DESIGN FOR A PLATE

Application filed August 17, 1929. Serial No. 32,429. Term of patent 14 years.

To all whom it may concern:

Be it known that I, HARRY BARKBY, a subject of the King of Great Britain, and residing at New Castle, in the county of Lawrence and State of Pennsylvania, U. S. A., have invented a new, original, and ornamental Design for a Plate, of which the following is a specification, reference being had to the accompanying drawing, forming a part thereof, which shows a top plan view of a plate showing my new design, it being understood that the ornamentation shown is continued throughout the border of the plate.

I claim:

The ornamental design for a plate, substantially as shown and described.

HARRY BARKBY.
